(57) **CLAIM**

The ornamental design for a combined circuit analyzer with surge protection and grip handles, as shown and described.

DESCRIPTION

FIG. 1 is a perspective view of a combined circuit analyzer with surge protection and grip handles showing my new design;

FIG. 2 is another perspective view thereof;

FIG. 3 is a right side view thereof;

FIG. 4 is a left side view thereof;

FIG. 5 is a front view thereof;

FIG. 6 is a back view thereof;

FIG. 7 is a bottom view thereof; and,

FIG. 8 is a top view thereof.
